UNITED STATES PATENT OFFICE.

THEODORE R. TIMBY, OF NYACK, NEW YORK.

COAST-DEFENSE.

SPECIFICATION forming part of Letters Patent No. 239,202, dated March 22, 1881.

Application filed January 10, 1881. (No model.)

To all whom it may concern:

Be it known that I, THEODORE R. TIMBY, a citizen of the United States, residing at Nyack, in the county of Rockland and State of New York, have invented Improvements in Coast-Defenses, of which the following is a specification.

The subject of my invention is a tower or turret mounted to revolve on a vertical axis on a bed or base, which latter is itself capable of rotation on a suitable foundation carrying the said tower or turret with it, so that if the tower is set in an eccentric position on the revolving base the revolution of the latter will carry the tower in an orbit around a center other than its own.

The invention further relates to mounting a revolving tower or turret on a revolving base in such a manner that the said turret may be adjusted radially on the revolving base, so as to be set in either eccentric or concentric position thereon.

In order that the invention may be fully understood, I will proceed to describe it with reference to the accompanying drawings, in which—

Figure 1 is a perspective view, showing the tower in central position on the base. Fig. 2 is a perspective view, showing the tower in eccentric position on the base. Fig. 3 is a plan, also showing the tower in eccentric position. Fig. 4 is a vertical section on the line 4-4, Fig. 3.

B represents a bed or base capable of revolution on a vertical axis on a suitable foundation, A, and having on its upper surface a suitable slot and ways (indicated at C) for the support and the adjustment to and from the center of a tower or turret, D, which latter is also capable of rotation on a vertical axis independently of the rotating base or bed B, by which it is supported and carried.

Adequate and suitable mechanism for im-

parting the required rotation to the bed or base B and the tower D on the said bed or base, 45 and moving or adjusting the tower D to or from the center of the bed or base, are within the knowledge of mechanics, and do not require specific description. Screw-gearing, racks, and pinions, or any suitable mechanical 50 appliances may be used for these purposes.

The tower or turret D is pierced with embrasures d for guns of any size or character. The revolving base or bed B may also constitute a casemate, being pierced with embrasures 55 for guns, as shown at d'.

From the above description it will appear that the revolving tower or turret D, when set in the center of the bed or base B, may derive its rotation from the rotation of the bed or 60 base, or may be rotated independently thereon, as preferred; but that when adjusted radially outward, as illustrated in Figs. 2, 3, and 4, the said tower, beside its ordinary functions as a revolving tower for the mounting and working of guns, can, by the independent movement of the revolving base or bed B on its own axis, be carried bodily to another position, and thus removed out of the range of an enemy's guns after they have been trained upon 70 it in the position first held.

Having thus described my invention, the following is what I claim as new therein and desire to secure by Letters Patent:

1. A bed or base revolving on a vertical axis, 75 in combination with a tower or turret mounted eccentrically thereon and revolving on a vertical axis other than that of the bed or base.

2. The combination of a revolving bed or base, and a tower or turret mounted thereon, 80 and capable of independent rotation and radial adjustment, as shown.

T. R. TIMBY.
